UNITED STATES PATENT OFFICE

CHARLES E. FYFE, OF CEDARHURST, NEW YORK

WHEEL CHOCK

Application filed April 19, 1929. Serial No. 356,349.

This invention relates to a wheel chock or device for preventing a car from rolling down an incline, and has for its main object and feature the production of means supported on the car or vehicle that can be readily and effectively brought into play and as readily rendered inactive when the occasion for its use no longer exists.

In the accompanying drawings the invention is disclosed in several concrete and preferred forms in which

Fig. 1 is a sectional view substantially on the plane of line 1—1 of Fig. 2 through the rear axle of an automobile, and showing one of the wheels thereof together with my improved chock and associated parts in elevation;

Fig. 2 is a top plan view of Fig. 1.

Fig. 3 is a view in rear elevation of the parts shown in Fig. 1 and looking in the direction of arrow 3 of said Fig. 1;

Fig. 4 is a detail sectional view substantially on the plane of line 4—4 of Fig. 2;

Fig. 5 is a detail sectional view substantially on the plane of line 5—5 of Fig. 3;

Fig. 6 is an enlarged side elevation, partly in section, of my improved chock;

Fig. 7 is a top plan view of Fig. 6, also partly in section;

Fig. 8 is a view in elevation looking in the direction of arrow 8 of Fig. 6;

Fig. 9 is a transverse sectional view substantially on the plane of line 9—9 of Fig. 6;

Fig. 10 is a fragmentary view in side elevation of the chock shown in Fig. 6, but disclosing the opposite side thereof;

Fig. 11 is a fragmentary top plan view of the left hand end of Fig. 7, showing a modification; and

Fig. 12 is a detail sectional view substantially on the plane of line 12—12 of Fig. 11.

The chock is in effect a cradle and consists here of a main cradle portion 1 and an auxiliary cradle portion 2 pivotally connected as at 3, each of the cradle portions being provided with a road-gripping bar or blade as 4 or 5. Any convenient or suitable means may be employed to support the chock and to bring it into and out of operation,

but, in the present instance, these means take the following form: 6 is a bracket suitably secured to hub 7 of the rear axle as by means of bolts 8. Said bracket is provided with ears 9 in which latter is pivotally carried, at 10, supporting arm 11 to which is attached in a manner to be presently described, the chock. It will be noted from Fig. 3 that pivot 10 is obliquely arranged with respect to the rear axle and that supporting arm 11 is likewise obliquely arranged so that the latter by turning on its pivot will carry the chock into position adjacent the wheel and roadway or out of the way up under the body of the car. 12 is a spring connected at one end to arm 13 of bracket 6 and at its other end to arm 11, said spring tending to urge arm 11 to carry the chock into position between the wheel and roadway. Normally said spring is restrained from so acting by means of a spring-pressed latch 14, seen best in Fig. 4, that engages an opening in projection 15 carried by arm 11 when the latter has moved the chock into inactive position. It will be apparent that the movement of the chock and of arm 11 may be controlled from a remote point such as the dash or instrument panel by suitable connections. In the drawings I have indicated two connections, one of which 16 is flexible and is connected to projection 15 and passes around a bearing point 17. It will be seen that, by pulling on connection 16, arm 11 will be so moved as to carry the chock into inactive position and this movement may continue until latch 14 registers with the opening in extension 15 when said latch will snap into position and will thereby prevent spring 12 from moving the chock into active position until the latch is released. The other connection 18 is for the purpose of controlling the release of the latch, and said connection is attached to bell crank 19 (Fig. 4) pivoted at 20 to bracket 6 and having an arm 21 that engages latch 14 and by means of which it is retracted from engagement with extension 15. When the operator therefore pulls on connection 18, latch 14 is retracted and spring 12 acts to bring the chock into active

position (Fig. 1). The connecting means between supporting arm 11 and the chock may vary widely, but as here shown these means take the following form: carried by 5 auxiliary cradle portion 2 is a guide 22 in which is mounted for up and down and lengthwise movement a bar 24. Attached to this bar is a yoke 25, carried by arm 11, and interposed between guide 22 and yoke 10 25 is a spring 26. 23 is a cotter pin to prevent withdrawal of bar 24 from guide 22. It will now be understood that when the operator releases latch 14, spring 12 will carry the chock into position shown in Fig. 15 1. Should the car now roll backward it will be apparent that the wheel will more fully engage the cradle and that in so doing there will be a movement of bar 24 with respect to guide 22 and that spring 26 will 20 be compressed. Likewise main cradle portion 1 will swing around center 3 so that blade 4 will engage the roadway first and thereafter, upon continued movement of the wheel, blade 5 will engage the roadway. It 25 will thus be seen that pivot 3, guide 22, bar 24 and spring 26 constitute a yielding connection that admits of the vehicle moving more intimately into engagement with the cradle after the chock is initially presented 30 between the wheel and roadway. Means are further provided to admit of lateral self-adjustment of the cradle when engaging the road and wheel. As here shown, arm 11 is provided with a joint as at 27 consisting of 35 a pin-and-slot connection as shown in Fig. 5, and a spring 28 to maintain the parts in central position. It will be understood that when the toe of the chock enters between the road and the wheel there may be 40 some slight obstruction or irregularity in the roadway and joint 27 will compensate for such irregularity as for want of proper adjustment of the arm. In effect the toe of the chock, when it engages the roadway 45 and wheel, becomes a fulcrum point around which the chock may swing, but the further engagement of the wheel with the chock will then tend to straighten the chock as will be apparent. If desired, the toe of the 50 chock may, as shown in Figs. 11 and 12, carry flanged disks 29 pivotally mounted at 30. In order to make the device fit different makes of cars, arm 11 may be made in two parts slidably adjustable as shown more 55 particularly in Fig. 3 and removable bolts 31 may be employed to fasten them together. The main cradle portion consists here of two side cheeks 32 connected together by means of a toe piece 33, chains 34 and trans- 60 verse cradle members 35. The auxiliary cradle member consists here of two side cheeks 36, connecting bars 37 and a trans- 65 verse cradle member 38. If desired, co-operating stops 39 may be employed on the main and auxiliary cradle portions.

I claim:

1. A wheel chock composed of a main cradle portion and an auxiliary cradle portion pivotally connected to successively engage the wheel and the roadway.

2. The combination with a wheel chock composed of a main cradle portion and an auxiliary cradle portion pivotally connected, of supporting means therefor on the vehicle, movable to present the main cradle portion of the chock between the roadway and a wheel, the action of the wheel thereafter moving the auxiliary cradle portion into engagement with the wheel and roadway.

3. The combination with a main cradle portion of a wheel chock, of supporting means therefor on the vehicle including: an auxiliary cradle portion pivotally connected to the main cradle portion, a guide carried by the auxiliary cradle portion, a bar slidably mounted in said guide, an arm connected to the bar, and a spring interposed between the guide and the arm.

Signed at Cedarhurst, in the county of Nassau, and State of New York, this 10th day of April, 1929.

CHARLES E. FYFE.
